his Atty's.

UNITED STATES PATENT OFFICE.

HENRY A. WOOD, OF EAST ORANGE, NEW JERSEY.

DESIGN FOR A GAME-BOARD.

No. 38,378.

Specification for Design.

Patented Dec. 18, 1906.

Application filed October 22 1906. Serial No. 340,100. Term of patent 7 years.

To all whom it may concern:

Be it known that I, HENRY A. WOOD, a citizen of the United States, residing at East Orange, New Jersey, have invented a new, original, and ornamental Design for Game-Boards, of which the following is a specification, reference being had to the accompanying drawing, forming part thereof.

The figure is a plan view of a game-board, showing my new design.

I claim—

The ornamental design for a game-board, as shown.

HENRY A. WOOD.
